ROTARY COMPRESSOR

Leonard F. Clerc, Nutley, N. J.

Application December 3, 1945, Serial No. 632,362

1 Claim. (Cl. 230—152)

1

This invention relates to compressors, and particularly to compressors of the rotary type employing vanes.

An object of the invention is the provision of a device of the character indicated, in which there is a cam action to positively control the movement of the vanes during an operating cycle.

Another object of the invention is the provision of a device of the character indicated, which has a cam action for controlling the movement of the vanes, and a series of rollers for guiding the vanes, whereby the friction generating contacting surfaces between the vanes and the rotor are reduced to a minimum.

Another object of the invention is the provision of a device of the character indicated, in which the ends of the vanes are maintained in predetermined spaced relation with the rotor and the inside surface of the housing at all times throughout the operating cycle.

Another object of the invention is the provision of a rotary compressor, in which all moving parts are lubricated through the action of the suction cycle of the device.

Another object of the invention is the provision of a device of the character indicated, which is compact in size, economical to manufacture, easy to assemble, and highly efficient in operation.

Another object of the invention is the provision of a device of the character indicated, in which the centrifugal force on the vanes is controlled by means of rollers engaging a cam surface.

The foregoing and other objects and advantages of the invention will become more apparent as the description proceeds, reference being made from time to time to the accompanying drawing forming part of the within disclosure, in which drawings:

Fig. 1 is a vertical sectional view of a device embodying my invention taken on the line 1—1 of Fig. 2.

Fig. 2 is a view taken substantially on the line 2—2 of Fig. 1.

Fig. 3 is a fragmentary section taken substantially on the line 3—3 of Fig. 2.

Fig. 4 is a section taken substantially on the line 4—4 of Fig. 2.

Fig. 5 is a section taken substantially on the line 5—5 of Fig. 2.

Fig. 6 is a section taken substantially on the line 6—6 of Fig. 2.

Fig. 7 is a vertical section taken on line 7—7 of Fig. 8 showing a modified form of my device.

2

Fig. 8 is a section taken on the line 8—8 of Fig. 7.

Fig. 9 is a section taken on the line 9—9 of Fig. 8.

Fig. 10 is a section taken on the line 10—10 of Fig. 8.

Fig. 11 is a perspective view of one of the vanes employed in the modification shown in Figs. 7 and 8.

Fig. 12 is a section taken on the line 12—12 of Fig. 8.

Referring now more particularly to the drawings (Figs. 1 and 2), it will be understood that in the embodiment herein disclosed, my compressor

15 consists of a housing 15, a rotor 16, and a cover plate 17, the latter being secured to the housing 15 by means of machine screws 18, 19 and 20 indicate guide pins for aligning the cover plate 17 with the housing 15.

20 The housing 15 and cover plate 17 are provided with recesses 21 and 22, in which are mounted suitable bearings 23 and 24, in which is adapted to rotate the shaft 25 upon which the rotor 16 is mounted. A sealing member 26 is 25 mounted about the shaft 25 in the cover member 17, and is adapted to prevent leakage around the shaft 25.

The rotor 16 is mounted concentrically on the shaft 25 but eccentric to the inside of the housing 15 and the cover plate 17. The rotor 16 is keyed as at 27 to the shaft 25 and is adapted to rotate therewith.

30 The rotor 16 is provided with a plurality of radially disposed slots 28, in which are adapted 35 to reciprocate the vanes 29, the latter being provided with transverse pins 30, on the ends of which are mounted rollers 31 which are adapted to engage a cam groove 32 formed in the inner wall of the housing 15.

40 Mounted in suitable recesses 33 formed in the rotor 16, on either side of the slots 28, are rollers 34, which rollers are supported on shafts 35 adapted to engage suitable bores 36 formed in the rotor 16 (Fig. 3).

The rollers 34 are crowned as shown in Fig. 3, and are adapted to contact grooves 29B formed in the vanes 29 to support and guide the vanes 29 in substantially frictionless engagement.

50 The housing 15 is provided with an intake opening 37 and an outlet opening 38 which is spaced more than 180 degrees beyond the intake opening 37. The inlet opening 37 communicates with a tapered slot 39 formed on the inside wall of the housing 15, which permits a full charge of gas to be interposed between each vane and the

vane following as the vanes pass the inlet opening 37. The length of the slot 39 is approximately equal to the distance between the centers of the outer ends of adjacent pairs of vanes.

I prefer to lubricate the device by means of an opening 40 in the housing 15 immediately below the intake opening 37 and a tube 41 which extends into the end of the shaft 25 and communicates with a plurality of radial passageways 42, formed in the shaft 25, which radial passageways communicate with a groove 43 and a plurality of radial bores 44 formed in the rotor 16, there being one bore 44 communicating with each vane slot 28, whereby upon each revolution of the rotor 16, the suction created causes a predetermined amount of lubricating medium to be drawn into the interior of the device.

In Figs. 7 to 12, inclusive, I disclose a modified form of the invention, which is similar to the construction just described, except that in this embodiment I eliminate the cam groove 32, transverse pins 36, and the rollers 31, and instead I provide a roller 45 at the end of each vane 29. In other respects, the housing 15A, the rotor 16A, the cover plate 17A, and the shaft 25A are constructed in the same manner as disclosed in Figs. 1 and 2.

In this embodiment, the vanes 29A are machined at their ends to engage the rollers 45, which are adapted to contact the inside surface of the housing 15A. The guide rollers 34A are cylindrical in shape and are adapted to engage wide grooves 46 formed in the vanes 29A. The effect of the rollers 45 contacting the inside surface of the housing 15A serves as a cam action to move the vanes 29A inwardly against the centrifugal force which tends to move them toward the housing.

In the embodiment disclosed in Figs. 1 and 2, the rollers 31 and cam groove 32 cooperate to hold the vanes 29 so that there is a slight clearance between the vanes 29 and the inside surface of the housing 15, which clearance is sealed by the lubricating medium hereinabove referred to.

In the modification shown in Figs. 7 and 8, there is a contact between the rollers 45 and the inside surface of the housing 15A. In the modified form, the lubricating medium will seal the required clearance between the rollers 45 and the vanes 29A.

Aside from the differences indicated above, the two structures will function in substantially the same manner, that is, as each vane is rotated into charging position, there is an impact between the vane 29 and the gas entering through the opening 37. As the vane continues past the opening 37, it creates a suction which causes further gas to be drawn into the slot 39 so that when the next succeeding vane reaches the position of impact, there is a full charge of gas between the vane and the preceding vane. As each vane receives its complete charge of gas, it carries its charge to a position substantially at the top center of the housing, at which instant the compression cycle commences. The compression of the gases continues in increased effectiveness until the gases are completely compressed and ready to be discharged through the opening 38.

With this device, I have been able to establish

a high degree of efficiency because of the positive control of the vanes and the substantial absence of friction between the moving parts.

With a device constructed and arranged as herein disclosed, I am able to obtain the maximum compressing action because of the positive control of the vanes. Particularly is this true in the embodiment disclosed in Figs. 1 and 2, where the reciprocation of the vanes is positively controlled by the cam action.

The outer cam surface of the groove 32 in Figs. 1 and 2 is particularly effective in improving the over-all capacity of this device for the reason that it positively moves the vanes 29 inwardly as the compression increases. The force of the increasing compression of the gases on the leading face of the vanes, together with the normal force of centrifugal action developed in conventional structures, causes the vanes to bind and ultimately freeze in position and causes undue wear, which rapidly reduces the efficiency of the device and requires greater motive power.

This positive movement of the vanes also improves the lubricating action of the device inasmuch as the inward movement of the vanes increases the pressure on the oil in the groove helping to force it around the vanes. This also effects a cushioning action at the end of the vanes which decreases the vibration of the parts and makes the operation of the compressor more quiet.

Having described my invention, what I claim and desire to secure by Letters Patent is:

In a device of the character described, including a housing having a rotor with radial slots therein and reciprocating vanes in said slots, the combination of a pair of recesses in said rotor in communication with each of said radial slots, and rollers in said recesses arranged to contact the sides of said vanes, said rollers being crowned, and said vanes being grooved to accommodate said crowns.

LEONARD F. CLERC.
